DESIGN FOR A SPECTACLE CASE

Laura Benner, New York, N. Y.

Application March 7, 1945, Serial No. 118,300

Term of patent 3½ years

(Cl. D57—1)

To all whom it may concern:

Be it known that I, Laura Benner, a citizen of the United States of America, residing at New York, county and State of New York, have invented a new, original, and ornamental Design for Spectacle Cases, of which the following is a specification, reference being had to the accompanying drawing, forming part thereof.

In the drawing:

Fig. 1 is a top plan view of a spectacle case showing my new design;

Fig. 2 is an end elevation of the spectacle case shown in Fig. 1.

Fig. 3 is a side edge elevation of the spectacle case shown in Fig. 1.

I claim:

The ornamental design for a spectacle case, substantially as shown.

LAURA BENNER.
